Co

United States Patent Office.

FRANK SAUNDERS, OF ABERDEEN, MISSISSIPPI.

Letters Patent No. 89,795, dated May 4, 1869.

SAFETY-LAMP.

The Schedule referred to in these Letters Patent and making part of the same.

To all whom it may concern:

Be it known that I, FRANK SAUNDERS, of Aberdeen, in the county of Monroe, and State of Mississippi, have invented certain new and useful Improvements in Safety-Lamps; and I do hereby declare that the following is a full, clear, and exact description of the same, reference being had to the accompanying drawing making a portion of this specification, which is a vertical transverse section of a lamp made according to my invention.

This invention consists in so arranging a vertical tube within the oil-reservoir of a kerosene or other lamp, as not only to provide a means whereby gases evolved from the oil may escape from the reservoir when their pressure exceeds that of external air, thus obviating danger of rupture or explosion from the accumulation of such gases, but also to secure the access of air to the reservoir, to fill the space vacated therein by the gradual removal of the oil when the lamp is in use.

The invention further consists in a feed-tube, funnel, and sliding valve, or piston, so arranged at the top of the oil-reservoir as to enable the reservoir to be filled with very great convenience, when required.

To enable others to understand the nature and construction of my invention, I will proceed to describe it with reference to the drawings.

The oil-reservoir, A, of the lamp may be of any suitable form and material, and provided at its top with a burner of any appropriate kind.

Such reservoir is designed to be situated upon the hollow pedestal B, furnished with a supporting-base, C.

Placed within the reservoir, in a nearly or quite upright position, is a tube, D, the open upper end of which is extended upward to a height above that of the surface of the oil when the reservoir is filled to the requisite degree, and which furthermore extends downward through the bottom of the reservoir, and through the pedestal, with its lower extremities opening below the latter.

When the lamp is in use, should the pressure of the gases generated from the oil in the reservoir exceed that of the external atmosphere, the excess of such gases will be caused to pass out therefrom through the tube D, thereby effectually preventing any explosion

or rupture of the reservoir, which might otherwise occur from the accumulation of the gases within the reservoir. Furthermore, as the oil is lowered in the reservoir by the combustion thereof, when the lamp is in use, the air passing upward through the tube occupies the space vacated thereby, as required to insure the proper burning of the flame.

Fitted into the top or upper part of the reservoir is a horizontal feed-tube, a, which, at its inner end, opens into the reservoir, but which may be closed at its outer end, as shown at a', and has at its upper side a funnel, b.

Passing through the closed end of this tube a is a stem, b', at the inner end of which is a valve, or piston, c, and which has coiled around it, a spiral spring, e, which forces the valve, or piston inward past the mouth, or orifice of the funnel, to wholly close the tube, thus providing against any escape from the reservoir of either liquids or gases, which might otherwise occur.

When it is desired to supply the reservoir with oil, the stem is drawn outward, to bring the valve, or piston to the outer side of the mouth, or orifice of the funnel, whereupon the oil, being poured into the funnel, passes through the tube a into the reservoir, the air displaced thereby passing outward through the tube D. When the reservoir is thus filled to the requisite degree, the stem b' is released, and the valve, or piston c being forced inward, as just mentioned, by the spring e, again closes the feed-tube a.

What I claim as my invention, and desire to secure by Letters Patent, is—

1. The arrangement of the vent D, passing through the bottom of the lamp-reservoir, and forming a free communication between the air-space therein and the external air through the stem and base of the lamp, substantially as shown and described, for the purpose set forth.
2. The feed-tube a, with its piston-valve e, and funnel b, in combination with the oil-reservoir A, all constructed, arranged, and operating substantially as shown and described, for the purpose specified.

FRANK SAUNDERS.
